MEANS FOR REGROOVING SPINDLE WHORLS

Walter C. Stewart, Gastonia, N. C.

Application December 23, 1933, Serial No. 703,693

2 Claims. (Cl. 82—6)

This invention relates to means for regrooving worn whorls on spindles whereby the sidewalls of the V-grooves in the whorl are cut away to form a groove in the whorl which, to all intents and purposes, serves the same purposes as new spindles having new whorls thereon.

It is an object of this invention to provide a machine for regrooving whorls on spindles wherein the spindle can be held in the machine and subjected to a plurality of successive operations to align and regroove the whorl on the spindle without the necessity of any adjustment between the successive operations.

It is another object of the invention to provide means for regrooving whorls on spindles comprising means for holding the spindle and rotating the same in a fixed position while a movable member having a plurality of tools therein is presented to the whorl to cause the tools to successively operate on the whorl to align the same, to cut the faces of the groove in the whorl and to finish the base and sidewalls of the whorl.

It is evident that when spindle whorls become worn that a groove is formed in the base thereof which renders them unsatisfactory for use in spinning frames and the like because it is compulsory that these whorls have a V-shaped groove therein and when a groove is worn by the cord or belt in the base thereof the belt is not properly gripped because the belt drives the whorl and spindle on the principle of a gripping effect being given to the belt on account of the sloping faces of the spindle whorl meeting at a common point. When the base of the whorl has become worn, as shown in Figure 1, it is evident that the gripping will not take place on the cord driving the spindle. It is an object of this invention to reface the groove in the spindle whorl to again provide the spindle whorl with a true V-groove therein.

Some of the objects of the invention having been stated, other objects will appear as the description proceeds when taken in connection with the accompanying drawings, in which:—

Figure 1 is a top plan view of the apparatus; Figure 2 is an elevation of the apparatus and looking at the lower side of Figure 1;

Figure 3 is an elevation of the right-hand end of Figures 1 and 2;

Figure 4 is a transverse sectional view and taken along the line 4—4 in Figure 2;

Figure 5 is an enlarged detailed sectional view of the means for holding the spindle and ejecting the same.

Referring more specifically to the drawings the

numeral 10 indicates a base plate having upstanding web members 11 and 12 at one end and a web or upstanding projection 13 near the other end, webs 11 and 12 being integral with each other. At the upper end of web 11 a bearing 14 is provided in which is rotatably mounted a hollow shaft 15 having secured on one end thereof driving means such as a pulley 16 and slidably mounted within the member 15 is a tubular member 17 normally pressed to the left in Figures 1 and 5 by means of a compression spring 18.

The right-hand end of member 15, as seen in Figure 5, has a tapered bore against which the slightly tapered portion 19 of the spindle is adapted to fit and whereby the spindle is given rotary motion when the member 15 is rotated. The tubular member 17 is adapted to receive the upper portion of the spindle, and the right-hand end thereof, as seen in Figures 1 and 5, is adapted to engage the portion 20 of the spindle to eject the same from the holding means 15.

On the upper end of web 11 an enlarged portion 25 is provided in which a shaft 26 is fixed by any suitable means such as a key 27.

The upper end of projection 13 has an enlarged portion 28 thereon which supports shaft 26. The right-hand end of shaft 26, in Figures 1 and 2, has rotatably mounted thereon a swinging member 29, which is loosely confined on shaft 26 by washer 30, and screw 31 embedded in the end of shaft 26. Member 29 has slidably mounted therein a holder 32 which is prevented from having turning movement in member 29 by means of a set screw 33 loosely engaging one of a plurality of longitudinally disposed grooves 34 in member 32. Member 32 is mounted between portions 35 and 36 of member 29 and has a spiral thread or screw 37 therein and rotatably mounted on shaft 32 is a collar 38 having a pin 39 therein which engages the screw or thread 37 so that when rotary movement is imparted to member 38, by means of a handle 40, the shaft 32 will be moved longitudinally to the right or the left in Figure 1, depending upon the direction of rotation of member 38.

Member 32, has in the left-hand end thereof, shown in Figure 1, a cavity made to conform to the shape of the tip 42 of the spindle so that the tip 42 of the spindle can have rotary movement in the seat provided in the end of member 32.

Threadably secured in the base plate 10 is a bolt 60 with a lock nut 61 thereon, the upper end of this nut being adapted to serve as a rest for member 29 when in operative position.

Mounted for sliding movement on shaft 26 is a member 44 having a slot 45 in the base thereof

penetrated by a screw 46 which is threadably mounted in base plate 10 for adjusting member 44 longitudinally of base plate 10.

Member 44 has parallel portions 47 and 48 and 5 in the upper ends of these portions 47 and 48 there is fixedly secured a shaft 49 having a sleeve 50 rotatably mounted thereon. Rotatably mounted on sleeve 50 is a tool holder 51 having a handle 52 threadably secured therein and adapted 10 to engage sleeve 50 when the handle is screwed home to bind the sleeve 50 and tool holder 51 together for unitary movement. This permits tool holder 51 and sleeve 50 to rotate together when the tool holder is rotated or partially rotated for 15 presenting the tools to the whorl. When handle 52 is unscrewed, tool holder 51 can be moved longitudinally of sleeve 50 so the tools will be aligned with the groove in the whorl. Tool holder 51 has a plurality of tools removably mounted 20 therein.

The tools 56 and 59 inclusive, are held in tool holder 51 by any suitable means, such as set screws 56a, 57a, 58a and 59a.

The spindle whorl is provided with sloping 25 faces 53 and 54 and is also shown as having a groove 55 worn therein by the cord or belt used for driving the same in a textile machine and it is an object of this invention to cut down the faces 53 and 54 to provide a groove having sloping 30 faces terminating in a point and to cut away the portions of sidewalls or faces of 53 and 54 to provide the new groove.

Tool 56 is provided, which is not a cutting tool but when the spindle is placed in position as 35 shown in the drawings the tool holder 51 is given a slight rotation, with handle 52 unscrewed and the tool 56 aligns and centers the tool holder with relation to the spindle whorl. After this alignment has taken place handle 40 is adjusted and 40 the tool holder is given a slight additional rotation, and cutting tool 57 is presented to the whorl to cut away the face 54 of the whorl and the tool may be shaped so as to cut away the base portions 45 of this face to a greater extent than the outer portions thereof. Next the tool holder is given a slight additional rotation to present cutting tool 58 to the spindle whorl to cut away the face 53 of the spindle whorl, thus causing the two faces to meet at a point in the base of the groove and 50 thus obliterating the worn groove 55.

Next the tool holder 51 is given a slight additional rotation to present tool 59 which cuts away a portion of both faces 53 and 54 and also the base 55 of the groove to dress and polish the same to provide a groove having uniform sidewalls meeting at a point in the base of the groove and thus providing a new groove in the spindle whorl which, to all intents and purposes, will cause the spindle to operate as well as if a new whorl has been 60 placed thereon.

Suitable set screws 46a and 46b are threadably secured in the lower portion of member 44 and

the ends of these screws contact base plate 10 to hold the lower end of member 44 against the head of set screw 46. It is evident that by loosening set screw 46 and tightening set screws 46a and 46b that the upper portion of member 44 and the cutting tool secured thereon, will be adjusted to a new position with relation to the whorl.

In operation, a spindle is placed into member 15 and member 29 is swung to the position shown in Figure 3 and then handle 40 of member 38 is also swung to the position shown in Figure 3 to move the shaft 32 against the tip 42 of the spindle to hold it in position where it can be rotated while the successive aligning and cutting operations are carried out. When these are carried out and it is desired to remove the spindle from the machine for the insertion of a new spindle therein, the handle 40 is moved in a counter clock-wise direction in Figure 3 until the handle engages a portion of member 29 and then further movement of handle 40 causes the member 29 to be also rotated in a counter clock-wise direction in Figure 3 to remove the entire apparatus supported by member 29, to the dotted line position shown in Figure 3 and out of the path of a spindle while being inserted into the machine or removed from the machine. By loosening the handle 52 the tools can be aligned with the groove in the whorl, as some spindle tips 42 may have been previously ground several times, thus making this lower portion of the spindle shorter in some instances than in others.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. Means for reforming worn grooves in whorls for textile spindles comprising revolving means for holding the spindle, an oscillating tool holder, an aligning tool mounted in the tool holder for aligning the whorl while it revolves, a plurality 120 of cutting tools mounted in the tool holder and adapted to be moved successively into cutting relation with the whorl to reform the groove upon one oscillation of the tool holder.

2. Means for reforming the groove in a whorl 125 of a textile spindle comprising revolving means of a textile spindle comprising revolving means for holding the spindle, pivoted means movable longitudinally of the spindle and having means for engaging the lower tip of the spindle for pressing the spindle into its holding means, an oscillating tool holder having a plurality of tools 130 radially disposed therein and being adapted to be successively presented to the whorl upon oscillation of the tool holder to successively operate upon the whorl while it is continuously revolving. 135

WALTER C. STEWART.
